UNITED STATES PATENT OFFICE.

PAUL JOSEPH LE GORIE, OF UNION HILL, NEW JERSEY.

COMBINED CHAIR AND CABINET FOR PHONOGRAHPS.

Application filed April 6, 1922. Serial No. 550,053.

To all whom it may concern:

Be it known that I, PAUL J. LE GORIE, a citizen of the United States, residing at 542 Jefferson Place, Union Hill, in the 5 county of Hudson and State of New Jersey, have invented certain new and useful Improvements in Combined Chairs and Cabinets for Phonographs, of which the following is a specification, reference being had 10 therein to the accompanying drawings.

This invention relates to a combined chair and cabinet for phonographs and it has for its object to so construct a device of this nature that a pleasing and ornamental article of furniture will be provided which will be of utility as a chair and at the same time will house the mechanism of the phonograph; certain of the elements of the phonograph being controllable, as hereinafter set 15 forth by a person seated in the chair.

It is a further object of the invention to make the chair in question serve the further useful purposes of providing a cabinet for the storage of phonograph records.

20 Further objects and advantages of the invention will be set forth in the detailed description which follows.

In the accompanying drawing:

Fig. 1 is a front perspective view of a 25 chair constructed in accordance with the invention;

Fig. 2 is a rear perspective view thereof with a part of the door of the cabinet broken away; and

Fig. 3 is a fragmentary sectional view 30 illustrating the member by which the sound controlling shutter is operated.

Like numerals designate corresponding parts throughout the several figures of the 35 drawing.

In carrying out the invention I provide a chair 5 of pleasing and ornamental appearance, the seat 6 of which is removable, as indicated in dotted lines in Fig. 1, so that 40 access may be had to a phonograph the casing of which is indicated at 7 and the mechanism of which may be wound by the usual crank indicated at 8. A sound controlling shutter 9 in the front wall of the 45 casing 7 provides means for determining the volume of sound which may pass from the phonograph and this shutter has its blades 10 connected to a vertical rod 11 which is provided with a finger engaging piece 12 50 upon its upper end so that the shutter may be controlled by a person seated in the chair

and without the necessity of arising. The back of the chair not only serves its usual function of constituting a back for the chair but also serves as a storage cabinet for 60 phonograph records indicated at 13. A door 14 provides for access to said cabinet. Thus it will be seen that the several elements of the chair are caused to serve double functions, the back is caused to serve as a 65 back and as a storage cabinet for the phonograph records. The seat is caused to serve its function as a seat and as a cover for the mechanism of the phonograph. The lower part of the chair is caused to serve 70 its usual function as an element of the chair and as a housing element for the phonograph mechanism, while the controlling element 12 of the shutter 9 is brought into such relationship to the chair frame as 75 to be accessible to a person seated in the chair.

The conserving of space is of importance in these days of small apartments and flats. The article of the present invention combines 80 all of the desirable qualities of an easy chair and of a phonograph while occupying only the space ordinarily occupied by one of them.

It is to be understood that the invention 85 is not limited to the precise construction set forth but that it includes within its purview whatever changes fairly come within either the terms or the spirit of the appended claims.

Having described my invention what I claim is:

1. In combination a chair frame, a phonograph case constituting a fixed and integral part of the chair frame and forming a completely closed housing lying beneath the seat portion of the chair frame and within the confines of the legs thereof, a liftable seat element constituting a seat for the chair and a cover for the phonograph case, sound 100 controlling elements mounted in one wall of the phonograph case, an operating member for the sound controlling elements accessible to a person seated in the chair and a horn element constituting a fixed and integral part of the structure and located within the phonograph case and terminating 105 adjacent said sound controlling elements.

2. In combination a chair frame, a phonograph case constituting a fixed and integral 110 part of the chair frame and forming a completely closed housing lying beneath the

seat portion of the chair frame and within the confines of the legs thereof, a liftable seat element constituting a seat for the chair and a cover for the phonograph case, 5 a horn element constituting a fixed and integral part of the structure and located within the phonograph case and sound controlling mechanism for said horn comprising an operating member accessible to a person seated in the chair and which sound controlling element controls the volume of sound passing from said horn. 10

3. In combination a chair, a phonograph casing housed in said chair beneath the seat

thereof, a seat element constituting a seat for the chair and a cover for the phonograph casing, a hollow back for the chair constituting a cabinet for the reception of phonograph records, a door through which records may be introduced to and removed from said hollow back, a sound controlling shutter in the front wall of the phonograph casing and a manually operable controlling member for said shutter accessible to a person seated in said chair. 15 20 25

In testimony whereof I hereunto affix my signature.

PAUL JOSEPH LE GORIE.
